UNITED STATES PATENT OFFICE.

MARK E. FERNALD, OF SAUGUS, MASSACHUSETTS.

GEOMETRICAL INSTRUMENT.

1,284,881.

Specification of Letters Patent. Patented Nov. 12, 1918.

Application filed March 22, 1915. Serial No. 16,049.

To all whom it may concern:

Be it known that I, MARK E. FERNALD, a citizen of the United States, residing at Saugus, in the county of Essex and State 5 of Massachusetts, have invented a new and useful Improvement in Geometrical Instruments, of which the following is a specification.

The present invention relates to geometrical instruments and more particularly to instruments for use in the manufacture of casting patterns.

It has been proposed to perform the various operations in the manufacture of 10 shoes automatically. In one system of automatic shoe machines the transfer of the point of operation of the tool along the work is controlled by a leader upon which the work supporting jacket is mounted, 15 These leaders usually comprise a body portion having the same area on one face as the projected area of the sole of the shoe mounted upon the jack and a flange on the edge of the body portion which is usually 20 provided with teeth for engagement with a driving pinion. The flange also acts as a guide for swinging the jack laterally to permit the tool to traverse the reverse curves 25 of the work. One of the principal objections to the use of these automatic machines is the cost of producing the leaders which 30 vary in size and shape with the various sizes and styles of soles intended to be incorporated into a shoe. As well known to 35 those skilled in the art it is necessary in making a casting pattern to allow for the shrinkage in the casting. Furthermore, in making a leader for a shoe machine it is also necessary to allow for the "spring" of 40 the last upon which the sole to be incorporated into the shoe is secured. The principal reason for the high cost of these leaders is that heretofore it has been necessary to employ a skilled pattern maker in 45 order to produce a sole-shaped blank having the metal shrinkage and the spring of the last measurements incorporated therein. I have conceived the idea of mechanically making casting patterns thus eliminating the need of a pattern maker and 50 thereby making a system of automatic machines an economical factor in the manufacture of shoes.

The object of the present invention is to produce an instrument which will accurately plot a blank for a casting pattern having either the metal shrinkage measurement or the spring of the last measurement, or both the metal shrinkage and the spring of the last measurements incorporated 55 therein.

To the accomplishment of this object a feature of the present invention contemplates the provision in a geometrical instrument of a form and a tracer engaged therewith relatively movable to transfer the point of engagement of the tracer around the form, and a recorder for recording the relative movement of the form and tracer plus an increment the amount of which is predetermined from a table of metal shrinkage. The form may be the casting or merely have the dimensions of the casting. In the specific embodiment of the invention the form is preferably the sole on a last. The 70 recorder may have any suitable mechanical embodiment found desirable or expedient. It is preferred, however, to employ a scribe for indicating or delineating the measurements of the blank for the casting pattern. 75

Another feature of the present invention contemplates the provision in a geometrical instrument of a support for a shoe last and a tracer arranged to engage the margin of a sole positioned on the last relatively movable to transfer the point of engagement of the tracer around the sole and generate an area equal to the projected area of the sole on the last. With this construction the 80 spring of the last measurement may be accurately determined. Broadly considered in accordance with the object of the invention this last named feature may be employed alone or combined with the first named feature so that a sole-shaped area 85 may be recorded or generated having the metal shrinkage and the spring of the last 90 measurements incorporated therein.

Other features of the invention relate to certain devices, combinations and arrangements of parts hereinafter described and then set forth broadly and in detail in the appended claims which possess advantages 95 readily apparent to those skilled in the art.

The various features of the present in- 100

105

vention will be readily understood from an inspection of the accompanying drawings showing the best form of the invention at present known to the inventor, in which,

5 Figures 1 and 2, taken together, are a plan of the geometrical instrument;

Figs. 3 and 4, taken together, are a side elevation;

Fig. 5 is a central vertical section; and,

10 Fig. 6 is a central vertical section of the tracer.

Describing now in general terms my novel method of making casting patterns which determine the form of the leaders employed 15 in automatic shoe machines, the first step consists in the production of the blank for the foundation of the pattern. As well known to those skilled in the art it is necessary in making a casting pattern to allow for 20 the shrinkage in the casting. Furthermore, in making a leader for a shoe machine it is necessary to allow for the "spring" of the last upon which the sole to be incorporated into a shoe is secured. To produce a sole-shaped blank having the metal shrinkage and the spring of the last measurements incorporated therein, I mount the sole upon a last and cause a tracer operatively connected to a recorder, such as a scribe, to travel 25 around the margin of the sole on the last. The tracer is mounted to generate a sole-shaped area equal to the projected area of the sole and the movement of the tracer in generating this area is transmitted to the 30 scribe. Interposed in the connections between the tracer and the scribe is a differential mechanism which enlarges, by the amount of the metal shrinkage, the movement imparted to the scribe by the tracer. 35 By this means a sole-shaped area is traced having the metal shrinkage and the spring of the last measurements incorporated therein. With this sole-shaped area as a guide a flat blank is made having the same size and 40 shape. This sole-shaped blank is then inserted into the machine disclosed in application Serial No. 868,921, filed by me October 27, 1914. This machine is provided with a rotatable support for the blank, devices for 45 supporting, guiding and feeding a strip of material, such as paper, and a pair of rolls for attaching the paper to the peripheral edge of the blank and winding the paper in layers thereon to build the guiding flange. 50 After the pattern is completed by this machine the draft necessary for the removal of the pattern from the sand is imparted to the pattern by a second machine which is disclosed in application Serial No. 869,336, filed 55 by Charles C. Blake, October 29, 1914, to which reference is made by permission. This machine is provided with a series of rolls which simultaneously support, guide, feed and operate automatically upon the pat-

tern to impart the draft thereto and remove 65 any roughness on the top and bottom faces of the flange. The pattern is then provided with a coat of oil or shellac.

In the illustrated embodiment of the invention a sole 1 (Figs. 2 and 4) is secured 70 to the bottom of a last 2 which is jacked upon a spindle 3 and a saddle 4 carried by the frame of the instrument.

In order to generate an area equal to the projected area of the sole on the last, which 75 is the area bounded by perpendiculars dropped from the edge of the sole to a plane, the margin of the sole is engaged by a tracer 6 (Figs. 4 and 6). The tracer comprises a frusto-conical roll 7 mounted to engage the face of the sole and a cylindrical roll 8 mounted to engage the edge of the sole. The roll 7 is mounted to rotate about an axis substantially parallel to the face of the sole 80 1 upon a stud 9 secured to a carrier 10 for 85 the tracer. The roll 8 is mounted to rotate about an axis substantially parallel to the edge of the sole on a race 11 which rotates on a collar 12 carried by a stud 13 on the carrier 10. To transfer the point of engagement of the tracer around the sole on the last the carrier 10 carries a handle 14 which is rotatably mounted on a race 15 carried by a collar 16 secured to the carrier 10.

In order that the tracer may adapt itself 95 automatically to the slope of the sole and to the reverse curvatures along its periphery the carrier 10 is loosely suspended by a cap 17 in a pair of races 18 which are mounted in boxes 19 formed in a support or truck 20 100 (Fig. 4). With this construction the carrier may rise and fall and rotate to maintain the rolls 7 and 8 properly engaged respectively with the face and edge of the sole on the last. As shown in Figs. 2 and 6 the axis 105 of rotation of the carrier 10 intersects the edge of the sole at the operating point.

In order to permit the tracer to move longitudinally of the sole the truck 20 carries a series of wheels 21 arranged to roll upon 110 the top and bottom edges of a rail 22. The movement of the truck 20 on the rail 22 is limited in both directions by pins 22A.

To permit the tracer to move laterally of the sole the rail 22 is mounted on a base 23 115 (Fig. 5) which is pivotally mounted on a post 24 (Fig. 5) carried by the frame of the instrument. To this end the base 23 is provided with a central conical bearing 24A arranged to engage a conical tip 25 on the post and a depending tube 26 which rotates on a race 27 carried by a collar 28 on the post.

With this construction the tracer may be engaged with the margin of the sole and transferred around the sole while engaged therewith. When the point of engagement of the tracer is transferred around the sole the carrier 10 automatically rotates to main-

tain the rolls 7 and 8 in their proper relation to the margin of the sole as the tracer travels along the reverse curvatures of the sole. The carrier 10 also rises and falls to accommodate the tracer to the slope of the sole. During the transfer of the point of engagement of the tracer around the sole the truck 20 rolls along the rail 22 thus permitting the tracer to be transferred longitudinally of the sole and the base 23 turns on its pivot to permit the tracer to be transferred laterally of the sole.

In order to record the movement of the tracer as it is transferred around the sole a rail 29 (Fig. 3) similar to the rail 22 carries a second truck 30 similar in construction to the truck 20. This truck 30 loosely carries a pencil or scribe 31 arranged to travel over a sheet of paper 32 (Fig. 1) removably secured to a board 33 the surface of which is arranged in a horizontal plane.

In order to transmit the movement of the tracer to the scribe the truck 20 is connected to a rack 34 which is guided and supported by three small rolls 35 (Fig. 4) and a large roll 36 (Fig. 5) which are mounted in a guideway 37 depending from the rail 22. The rack 34 meshes with a gear 38 (Fig. 5) which is rotatably mounted on a post 39 carried by the base 23 and arranged concentric to its axis. The gear 38 is pinned to a second gear 40 which meshes with a second rack 41 (Figs. 1, 3 and 5). The rack 41 is guided and supported by three small rolls 42 (Figs. 3 and 4) and a large roll 43 (Fig. 5) which are carried by a guideway 44 depending from the rail 29. The rack 41 is connected to the truck 30.

With this construction all the movements of the tracer, except its vertical and pivotal movements, are transmitted to the scribe. As the vertical and pivotal movements of the tracer are provided merely for the purpose of maintaining the tracer in proper relation to the margin of the sole as its point of engagement is transferred around the sole all the transferring movement of the tracer is transmitted to the scribe. As the rack 34 moves in all directions in a horizontal plane it is obvious that the tracer generates an area which is equal to the projected area of the sole, that is, an area bounded by perpendiculars dropped from the edge of the sole to a plane.

From this construction so far described it is clear that if the gears 38 and 40 are provided with the same number of teeth the scribe will delineate upon the sheet of paper 32 an area equal to the area generated by the tracer. In order, however, to enlarge the movement of the scribe responsive to the movement of the tracer by an increment the amount of which is predetermined from the known shrinkage of the metal of

which the leader is to be made the gears 38 65 and 40 are provided with different numbers of teeth the ratio of which is calculated from the following table:—

Table of metal shrinkage.

Metal.	Shrinkage per foot.	Ratio of gears.	70
Cast iron.....	$\frac{1}{8}$ inch.	96 to 97	
Brass.....	$\frac{1}{16}$ "	192 to 195	75
Steel.....	$\frac{1}{16}$ "	48 to 49	
Malleable iron.....	$\frac{1}{16}$ "	96 to 97	
Zinc.....	$\frac{1}{16}$ "	192 to 197	
Tin.....	$\frac{1}{16}$ "	24 to 25	
Bismuth.....	$\frac{1}{16}$ "	384 to 389	
Aluminum.....	$\frac{1}{16}$ "	192 to 195	
Britannia.....	$\frac{1}{16}$ "	384 to 385	

80

For instance, if the leader for use in the automatic shoe machine were made of cast iron the table of metal shrinkage would be consulted where it would be found that cast iron shrinks $\frac{1}{8}$ inch per foot and that the ratio of the teeth in the gears should be 96 to 97 in order to enlarge the movement of the scribe, responsive to the movement of the tracer, by an increment the amount of which is $\frac{1}{8}$ inch per foot. In order therefore to plot a blank for a pattern for use in making iron castings the gear 38 should have 96 teeth and the gear 40 should have 97 teeth. While the primary object of the present invention is directed to a narrow field in the art of metal-founding, I believe that I am the first to have conceived the idea for the mechanical production of casting patterns and to have devised operative mechanism for carrying such idea into practice. Consequently, the primary object of the present invention is not to be understood as limiting the scope of the claims, where the context otherwise permits, to an instrument for use in making patterns for casting leaders for automatic shoe machines as it will be apparent to those skilled in the art that an instrument having the features and combinations of parts hereinbefore described is well adapted for general use in making casting patterns.

It will be apparent to those skilled in the art that the table of metal shrinkage set forth herein includes only the metals and alloys generally employed in casting. In the event that some other metal or alloy were to be used in casting, the shrinkage of said metal or alloy would first be determined and the ratio of the teeth of the gears 38 and 40 calculated from the determined shrinkage. Obviously other metals or alloys may be added to the table of metal shrinkage herein set forth without departing from the spirit of the invention. It will also be apparent that the traveling scribe 31 may indicate directly upon the material, such as wood or cardboard, for the blank.

It will be clear to those skilled in this

125

class of machines and with the general objects of the present invention in view, that changes may be made in the details of structure, the described and illustrated embodiment thereof being intended as an exploitation of its underlying essentials the features whereof are definitely stated in their true scope in the claims herewith.

What is claimed as new, is:—

- 10 1. A geometrical instrument, having, in combination, a support for a form and a tracer engaged with the form relatively movable to transfer the point of engagement of the tracer around the form, and a recorder responsive to the relative movement of the form and tracer for recording said movement plus an increment the amount of which is predetermined from a table of metal shrinkage, substantially as described.
- 15 2. A geometrical instrument, having, in combination, a support for a form and a tracer engaged with the form relatively movable to transfer the point of engagement of the tracer around the form, a recorder responsive to the relative movement of the form and tracer, and means for amplifying the indication of the recorder by an increment the amount of which is predetermined from a table of metal shrinkage, substantially as described.
- 20 3. A geometrical instrument, having, in combination, a support for a shoe last and a tracer, engaged with a sole positioned on the last relatively movable to transfer the point of engagement of the tracer around the sole on the last, and a scribe responsive to the relative movement of the support and tracer arranged to record said movement plus an increment the amount of which is predetermined from a table of metal shrinkage, substantially as described.
- 25 4. A geometrical instrument, having, in combination, a support for a shoe last, a tracer, arranged to engage a sole positioned upon the last, movable to transfer the point of engagement of the tracer around the sole, and a scribe responsive to the movement of the tracer arranged to record said movement plus an increment the amount of which is predetermined from a table of metal shrinkage, substantially as described.
- 30 5. A geometrical instrument, having, in combination a support for a shoe last, a tracer, arranged to engage a sole positioned upon the last, movable to transfer the point of engagement of the tracer around the sole, a scribe arranged to respond to the movement of the tracer, and means for amplifying the movement of the scribe responsive to the movement of the tracer by an increment the amount of which is predetermined from a table of metal shrinkage, substantially as described.
- 35 6. A geometrical instrument, having, in combination, a support for a form and a tracer engaged with the form relatively movable to transfer the point of engagement of the tracer around the form, a recorder responsive to the relative movement of the form and tracer for recording said movement plus an increment the amount of which is predetermined from a table of metal shrinkage, substantially as described.
- 40 7. A geometrical instrument, having, in combination, a support for a shoe last, a tracer arranged to engage the margin of a sole positioned upon the last, movable to generate an area equal to the projected area of the sole on the last, a recorder responsive to the movement of the tracer, and means for amplifying the indication of the recorder by an increment the amount of which is predetermined from a table of metal shrinkage, substantially as described.
- 45 8. A geometrical instrument, having, in combination, a support for a shoe last, a tracer, arranged to engage the margin of a sole positioned upon the last, movable to generate an area equal to the projected area of the sole on the last, a scribe responsive to the movement of the tracer, and means for amplifying the movement of the scribe responsive to the movement of the tracer by an increment the amount of which is predetermined from a table of metal shrinkage, substantially as described.
- 50 9. A geometrical instrument, having, in combination, a support for a shoe last, a tracer arranged to engage the margin of a sole positioned upon the last, said support and tracer being relatively movable in the direction of the length and width of the last to transfer the point of engagement of the tracer around the sole and also in the direction of the height of the last to accommodate for variations in the slope of the sole, a scribe, and connections between the tracer and the scribe constructed and arranged to transmit to the scribe the relative lengthwise and widthwise movements of the support and tracer, substantially as described.
- 55 10. A geometrical instrument, having, in combination, a support for a shoe last, a tracer, arranged to engage the margin of a sole positioned upon the last, movable in the direction of the length and width of the last to transfer the point of engagement of the tracer around the sole and also in the direction of the height of the last to accommodate for variations in the slope of the sole, a scribe, and connections between the tracer and the scribe constructed and arranged to transmit to the scribe the lengthwise and widthwise movements of the tracer, substantially as described.
- 60 11. A geometrical instrument, having, in combination, a support for a form and a tracer engaged with the form relatively movable to transfer the point of engagement of the tracer around the form, a

combination, a support for a shoe last and 65 a tracer arranged to engage the margin of a sole positioned upon the last, relatively movable to transfer the point of engagement of the tracer around the sole and generate an area equal to the projected area of the 70 sole on the last, substantially as described.

7. A geometrical instrument, having, in combination, a support for a shoe last, a tracer, arranged to engage the margin of a sole positioned upon the last, movable to 75 generate an area equal to the projected area of the sole on the last, a recorder responsive to the movement of the tracer, and means for amplifying the indication of the recorder by an increment the amount of which is 80 predetermined from a table of metal shrinkage, substantially as described.

8. A geometrical instrument, having, in combination, a support for a shoe last, a tracer, arranged to engage the margin of a 85 sole positioned upon the last, movable to generate an area equal to the projected area of the sole on the last, a scribe responsive to the movement of the tracer, and means for amplifying the movement of the scribe 90 responsive to the movement of the tracer by an increment the amount of which is predetermined from a table of metal shrinkage, substantially as described.

9. A geometrical instrument, having, in 95 combination, a support for a shoe last, a tracer arranged to engage the margin of a sole positioned upon the last, said support and tracer being relatively movable in the direction of the length and width of the last 100 to transfer the point of engagement of the tracer around the sole and also in the direction of the height of the last to accommodate for variations in the slope of the sole, a scribe, and connections between the tracer 105 and the scribe constructed and arranged to transmit to the scribe the relative lengthwise and widthwise movements of the support and tracer, substantially as described.

10. A geometrical instrument, having, in 110 combination, a support for a shoe last, a tracer, arranged to engage the margin of a sole positioned upon the last, movable in the direction of the length and width of the last to transfer the point of engagement of the tracer around the sole and also in the direction of the height of the last to accommodate for variations in the slope of the sole, a scribe, and connections between the tracer 115 and the scribe constructed and arranged to transmit to the scribe the lengthwise and widthwise movements of the tracer, substantially as described.

11. A geometrical instrument, having, in 125 combination, a support for a form and a tracer engaged with the form relatively movable to transfer the point of engagement of the tracer around the form, a

- scriber, and a differential connection between the tracer and the scribe for enlarging the movement of the scribe responsive to the relative movement of the form and tracer by an increment the amount of which is predetermined from a table of metal shrinkage, substantially as described. 5
12. A geometrical instrument, having, in combination, a support for a form, a tracer 10 arranged to engage the form and movable to transfer the point of engagement of the tracer around the form, a scribe, and a differential connection between the tracer and the scribe comprising a pair of gears having different numbers of teeth the ratio of 15 which is calculated from a table of metal shrinkage, substantially as described.
13. A geometrical instrument, having, in combination, a support for a form, a tracer 20 arranged to engage the form and movable to transfer the point of engagement of the tracer around the form, a rack connected to the tracer, a gear engaged by the rack, a second gear having a different number of 25 teeth than the first gear arranged to rotate with the first gear, a second rack engaged by the second gear, and a scribe connected to the second rack, substantially as described.
- 30 14. A geometrical instrument, having, in combination, a support for a form, a tracer arranged to engage the form and movable to transfer the point of engagement of the tracer around the form, a scribe, and connections 35 between the tracer and scribe comprising a pair of racks longitudinally movable and rotatable in a horizontal plane, substantially as described.
15. In a geometrical instrument, a tracer 40 comprising a frusto-conical roll arranged to engage the face of a form and a cylindrical roll arranged to engage the edge of the form, substantially as described.
16. A geometrical instrument, having, in 45 combination, a tracer comprising a roll arranged to engage the face of a form and a roll arranged to engage the edge of the form, and a carrier for the tracer mounted
- to rotate about an axis substantially normal to the face of the form and to slide in the direction of extent of said axis, substantially as described. 50
17. In a geometrical instrument, a support for a shoe last and a tracer comprising a pair of rolls arranged to engage respectively 55 the face and edge of a sole positioned on the last and mounted to rotate about axes substantially parallel to the respective engaged surfaces, substantially as described.
18. A geometrical instrument, having, in 60 combination, a support for a shoe last, a tracer arranged to engage a sole positioned on the last, a carrier for the tracer mounted to rotate about an axis substantially normal to the face of the sole, to slide vertically, 65 and to move longitudinally and laterally of the sole on the last, substantially as described.
19. A geometrical instrument, having, in 70 combination, a support for a form, a tracer, arranged to engage the form movable to transfer the point of engagement of the tracer around the peripheral edge of the form and rotate about an axis coincident with said edge to adapt itself to the varying 75 curvatures of the form, and a handle for moving the tracer around the form, substantially as described.
20. A geometrical instrument, having, in 80 combination, a support for a form, a tracer, arranged to engage the form, movable to transfer the point of engagement of the tracer around the form and mounted to rotate and slide vertically on its axis of 85 rotation, and a handle for moving the tracer around the form connected to move vertically with the tracer, substantially as described.
21. A geometrical instrument, having, in 90 combination, a support for a last having its bottom curved laterally and longitudinally, and means for projecting the edge of a sole secured to the bottom of the last upon a plane, substantially as described.

MARK E. FERNALD.
